(57) **CLAIM**

The ornamental design for an electric terminal, as shown and described.

DESCRIPTION

FIG. 1 is a top, front, right perspective view of an electric terminal showing our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

Broken lines formed by equal length dashes show unclaimed portions of the design. Broken lines formed of unequal length dashes (i.e., dash-dot) show boundaries between claimed and unclaimed portions of the design. The equal length broken lines having a jagged z-shaped element form no part of the claimed design and are shown broken away to indicate that no particular length or width of the portion between the break lines is claimed.
